UNITED STATES PATENT OFFICE.

CHARLES H. BOECK, OF JACKSON, MICHIGAN, ASSIGNOR TO THE NOVELTY MANUFACTURING COMPANY, OF SAME PLACE.

DESIGN FOR AN OIL-STOVE.

SPECIFICATION forming part of Design No. 23,971, dated January 29, 1895.

Application filed September 18, 1894. Serial No. 523,417. Term of patent 7 years.

To all whom it may concern:

Be it known that I, CHARLES H. BOECK, a citizen of the United States, residing at Jackson, in the county of Jackson and State of Michigan, have invented and produced a new and original Design for Oil-Stoves, of which the following is a specification, reference being had to the accompanying drawings.

The invention relates to a new and original design for oil stoves, and consists in the peculiar arrangement and shape of the parts, hereinafter referred to and illustrated.

In the accompanying drawings Figure 1 is a front elevation of a stove embodying the design, and Fig. 2 is a side elevation thereof.

A represents the top of the frame; B, the supporting frame, and C a drum shaped oil tank, arranged near the bottom of the frame, and between the sides thereof.

D is a hoop forming a band centrally about the tank, connected at opposite sides to the sides of the frame.

Centrally from the top of the tank extends

upwardly the cylindrical wick tube E on which is the cylindrical combustion chamber F terminating in the ring or collar G below the stove top.

The essential features of the design are the flat cylindrical or drum-shaped oil tank, the cylindrical wick tube E at the center of the upper face of the tank and of relative small diameter, and the cylindrical combustion chamber of larger diameter than the tube and the collar G on the upper end of the chamber; the whole disposed within the rectangular frame, as shown.

What I claim as my invention is—
The design for an oil stove substantially as herein shown and described.

In testimony whereof I affix my signature in presence of two witnesses.

CHARLES H. BOECK.
